UNITED STATES PATENT OFFICE.

OROSCO CHARLES WOOLSON, OF NEWARK, NEW JERSEY.

ROPE-DRIVING APPARATUS.

SPECIFICATION forming part of Letters Patent No. 285,095, dated September 18, 1883.

Application filed May 7, 1883. (No model.)

To all whom it may concern:

Be it known that I, OROSCO CHARLES WOOLSON, a citizen of the United States, residing at the city of Newark, county of Essex, and State of New Jersey, have invented a new and useful Improvement in Rope-Driving Apparatus, of which the following is a specification, reference being had to the drawings thereof, which form part of this specification.

10 Figure 1 represents a plan of the whole gearing. Fig. 2 represents a side elevation of the same, neither of which figures has any framework attached.

15 This invention relates to that class of mechanisms employed for elevators and rope traction.

20 The object of my invention is to prevent the slipping of the contact driving-faces of the drums other than that due to expansion or contraction of traction-rope, and to afford an auxiliary driving medium to the rope-drums, and at the same time not to impair the usefulness of the intermediate driving-drum as an anti-friction bearing.

25 The drawings show a gear-wheel on each rope-drum; but that is not necessary to my invention, for the same end can possibly be attained by only attaching a gear-wheel to one of the rope-drums and the intermediate or 30 anti-friction driving-drum.

To enable others to understand the drawings, I will describe them in detail, and will subsequently define the novel features thereof.

35 A and *a* represent the friction - driven drums; *b*, the intermediate anti-friction driving-drum; C, the driving-shaft, having a crank-disk, F and *f*, to couple the engine or other motor; D and *d*, the shafts which carry the rope-drum; E and *e*, the fly-wheels to give 40 steadiness to the rotation of the drums; G and *g*, the gear-wheels connected to the rope-drums; *h*, the intermediate driving-pinion, connected to the driving-drum *b*.

The action of this mechanism is as follows: 45 The rope is brought down, as shown in the drawings at the right, and passes around the drums A and *a* several times, and then up to

the left, as shown on the drawings. This rope, being the hoisting or traveling traction-rope and traversing the drums, as described, necessarily brings great pressure on the contact friction faces of drums at *i i*, thus affording the requisite driving friction for the motive power, the portions of the rope-drums A and *a* containing the grooves or ropeway being of 55 smaller diameter than the friction-faces of the said drums to avoid the possibility of grease and other foreign matter being carried to or falling upon the friction-faces *i i*.

It will be readily understood that, if the motive power were required to transmit all its motion through the medium of these friction-faces *i i* alone, there would be a time, under the varying conditions of operation when these faces would slip one upon the other, which 65 would be a serious objection and render the mechanism impracticable and useless. The gear-wheels are therefore intended as the auxiliary and the friction-faces *i i* of the drums the primary motive power.

70 What I claim as new, and desire to secure by Letters Patent, is—

1. The gear-wheels G and *h*, in combination with the drums A, *a*, and *b*, having friction-faces *i i* formed on a portion of the drums' 75 peripheries.

2. The gear-wheels G and *g* and *h*, in combination with drums A and *a* and *b*, made substantially in the manner herein specified, having friction-faces *i i* formed on a portion of 80 the drums' peripheries and grooves or other adequate space formed on another portion of the drums' peripheries, substantially as described.

3. The gear-wheels G and *h*, in combination 85 with the drums A, *a*, and *b*, having friction-faces *i i* formed on a portion of the drums' peripheries and grooves or other adequate space formed on another portion of the drums' peripheries.

OROSCO CHARLES WOOLSON.
